UNITED STATES PATENT OFFICE.

ERNST W. DITTMANN, OF LEIPSIC, SAXONY, GERMAN EMPIRE.

IMPROVEMENT IN BAKERS' OVENS.

Specification forming part of Letters Patent No. **222,677**, dated December 16, 1879; application filed September 16, 1879; patented in Germany, January 19, 1879.

To all whom it may concern:

Be it known that I, ERNST WILHELM DITTMANN, of the city of Leipsic, in the Kingdom of Saxony, German Empire, have invented a new and Improved Baker's Oven, for which Letters Patent have been granted to me for the German Empire, dated January 19, 1879, and numbered 6,137, of which the following is a specification.

In the accompanying drawings, Fig. 1 represents a top view, partly in horizontal section, of my improved baker's oven; Fig. 2, a vertical longitudinal section on line *x x*, Fig. 1; Fig. 3, an end elevation, and Fig. 4 a vertical transverse section of the same on the line *y y*, Fig. 2. Fig. 5 is a sectional plan view on line *z z*, Fig. 2.

Similar letters of reference indicate corresponding parts.

This invention relates to an improved baker's oven, which is heated up jointly by steam and by the gases of combustion of the furnace of the steam-generating boiler, so as to admit of a continuous baking process, be fully within control, and produce a considerable saving in time and fuel and a superior product.

The invention consists of an oven the hearth-plate of which is enameled, and heated from below by steam, while the side, back, and top plates are heated by the direct action of the gases of combustion that are drawn over the same from the furnace of the steam-generating boiler. Steam is also admitted to the interior of the oven by steam-pipes for supplying the required moisture to the articles to be baked therein.

Referring to the drawings, A represents the oven, which is made entirely of iron plates and supported on a foundation, B, of brick. The foundation B is inclined in the usual manner, the oven partaking of the same inclination. Below the hearth-plate C of the oven is formed a space, D, by a base-plate, C', and by side and rear plates C². This space is heated by steam supplied from a boiler. The upper surface of the hearth-plate C is covered with white enamel, for the purpose of easily distinguishing the articles thereon. Above the top plate of the oven is formed a second space, E, which is inclosed by a brick top arch and by side and rear brick walls. Into the top space E are con-

ducted the gases of combustion from the furnace F of the boiler F', said gases providing the top heat for the articles to be baked. The mouth or entrance of the oven is contracted toward the inside and closed by a sliding door.

The steam is supplied to the bottom steam-space, C, from the boiler F' by a pipe, D', which enters into the same near the mouth of the oven. The pipe D' is provided with a valve for regulating the supply of steam.

The boiler F' may be arranged in any suitable relative position to the oven, according to the space available for the same. The gases of combustion pass from the furnace through a flue, G, to the upper space, E, and beyond the top plate to a flue, G', at the rear part of the oven, thence along the rear wall, and through side flues G², along the side walls of the oven, and thence to the chimney. The rear flue, G', and side flues, G², however, are arranged at some distance above the hearth-plate, so as not to exert too great heat on the articles near the side and rear walls and cause the burning of the same. The flues are extended through the inclosing brick walls, and closed by small doors to admit of ready cleaning.

The boiler and its furnace furnish not only the required constant bottom heat, but also the less constant top heat for the articles to be baked. This is accomplished with a considerable saving of fuel, and in such a manner that a continuous working of the oven is possible. The interior temperature is indicated by a thermometer, t, so that the attendant is enabled to keep up the proper temperature in the oven by properly setting the valve of the steam-pipe and damper of the flue G.

This arrangement gives complete control over the oven, and furnishes a uniform baking process throughout, which is not the case with the common ovens, as the heating in the latter, owing to the method of heating the same, is at first too great, and afterward too weak, so as not to turn out a uniformly-baked product, but one which has partly baked too much and partly too little.

From the steam-supply pipe D' branch off two valved pipes, D², which pass through the front brick wall above the mouth of the oven to the interior of the same. The pipes D² extend with a slight upward inclination toward

the rear corner of the oven, and are open at the rear ends, so as to supply the required moisture for baking. As the steam is emitted from the pipes at the rear part of the oven it has to pass over all the articles before it reaches the mouth and can escape to the outside. The articles are, by the presence of moisture, baked in a superior manner, and with a crisper and more uniform crust.

The water of condensation passes off through suitable exit pipes at the lowermost points of the bottom steam-space. The steam may, however, be superheated, if desired, by using an approved superheating apparatus in connection with the boiler.

Having thus described my invention, I claim as new and desire to secure by Letters Patent—

1. The combination of an oven made of metal plates and provided with a steam-space below the hearth-plate, with a heating-space formed by an arch above the oven, with a steam-generator and furnace, and with connecting steam-pipes and flues to supply steam-heat to the bottom and the heat of the gases of combustion to the top of the oven, substantially as described.

2. The combination of a baker's oven, made of metal plates, and provided with a steam-space below the hearth-plate, and with a top space, with a furnace, a connecting main flue, and with rear and side flues, the latter being arranged above the hearth-plate of the oven, and connected to the chimney, substantially as specified.

3. The combination of a baker's oven with interior steam-supply pipes, which extend at an upward inclination from the front to the rear part of the oven, and are open at the rear end to supply the required moisture for baking, as set forth.

4. In the art of baking, the method herein described, of applying simultaneously a constant steam-heat to the bottom, a less constant but direct heat to the top of the oven, and steam to the inside of the same, substantially as described.

In testimony whereof I have signed my name to this specification in the presence of two subscribing witnesses.

ERNST WILHELM DITTMANN.
